(57) **CLAIM**

The ornamental design for a cutting disc as shown and described.

DESCRIPTION

FIG. 1 is a front, top, and right side perspective view of a cutting disc according to a first embodiment of my new design;

FIG. 2 is a front elevation view thereof;

FIG. 3 is a rear, top, and right side perspective view thereof;

FIG. 4 is a bottom plan view thereof;

FIG. 5 is a front, top, and right side perspective view according to a second embodiment;

FIG. 6 is a front elevation view thereof;

FIG. 7 is a rear, top, and right side perspective view thereof; and,

FIG. 8 is a bottom plan view thereof.

The left views of the embodiments have been omitted because they are symmetrical to the corresponding right views.

The broken lines in the drawings depict portions of the cutting disc that form no part of the claimed design.
